UNITED STATES PATENT OFFICE.

JAMES P. KARR, OF MONTICELLO, INDIANA.

STEAM-BOILER.

No. 802,812.

Specification of Letters Patent.

Patented Oct. 24, 1905.

Application filed April 6, 1904. Serial No. 201,842.

To all whom it may concern:

Be it known that I, JAMES P. KARR, a citizen of the United States, residing at Monticello, in the county of White and State of Indiana, have invented certain new and useful Improvements in Steam-Boilers, of which the following is a specification.

This invention relates more particularly to an attachment to steam-boilers, and has for its object to provide means whereby the boiler capacity may be increased over steam-boilers as heretofore constructed and without corresponding increase of fuel consumption.

The invention consists, broadly stated, of a portable independent section adapted to be placed at the rear end of return-flue boilers or the smoke-box end of direct-draft boilers.

Specifically stated, it consists of the special construction, combination, and arrangement of parts shown by the accompanying drawings and hereinafter fully described, the novel features being pointed out in the appended claims.

In the drawings, Figure 1 is a vertical longitudinal sectional view showing a broken-away rear end of a return-flue steam-boiler with my improved attachment applied thereto, the section being taken in line direct through the attachment. Fig. 2 is an inner plan view of my attachment; and Fig. 3 is a view similar to Fig. 1, but illustrating my attachment applied to the smoke-box end of a direct-draft steam-boiler.

In the practice of my invention I employ a suitable box or shell A, constructed with an outer sheet or hull B, an inner sheet C, an outer head D, and an inner head E, having laterally-disposed tubes F. The latter have their free or projecting ends G closed and their inner space made communicating through openings H with the water I within the box or shell attachment A. At the front end of the box or shell I arrange a suitable sheet J, closing the water and steam spaces I K. The sheet J is constructed with an opening L corresponding to the recess M in the box or shell A formed by the inner sheet C and the inner head E. The tubes F are arranged on the inner head E, leaving a lower unobstructed portion M' in the recess M, as shown in Figs. 1 and 2.

At the under side of my attachment I arrange an opening N, leading in the space M', and I also provide a similar opening O, leading into said space M' from the rear of my attachment. The openings N O are designed

for clean-out purposes and the latter thereof adapted for use as will appear farther on. P denotes a steam-pipe having a suitable coupling Q in its length and adapted for providing 60 passage-way between the steam-space K of my attachment and the steam-space R of the boiler S.

It will be understood that proper water passage-way should be provided between my 65 attachment A and the boiler S and also that the attachment be suitably secured to the end of the boiler S.

The water passage-way referred to may be located at any suitable position affording free 70 circulating connection. It is indicated by dotted line A² in Fig. 1 and transverse section or open end view in Fig. 2.

In the use of my invention as illustrated in Fig. 1 at the rear end of a return-flue boiler 75 it is apparent that much additional heating-surface is provided over all similar boilers having this end thereof closed by the well-known brick or other similar arch.

The attachment is equally adapted for use 80 with a direct-draft boiler, as indicated in Fig. 3. In this connection or use of my invention a suitable smoke-uptake T is arranged in rear of the attachment and made communicating with its space M' through the rear opening 85 O, which latter should be constructed to provide adequate passage-way for all products of combustion leading from the space M' into the uptake T.

My invention will be understood from the 90 above description. It forms an attachment or section to a steam-boiler whereby the steam-making capacity is materially increased over all similar boilers as heretofore constructed, and the improved generating capacity being 95 effected through minimum consumption of fuel. A boiler attachment or section constructed according to my invention has further advantage in being portable in nature and readily attachable to return-flue and direct-draft boilers as the same are now constructed.

Having thus described my invention, what I claim as new, and desire to secure by Letters Patent, is—

1. A supplemental section for steam-boilers, consisting of an outer hull, inner and outer sheets or heads held spacedly apart by the hull, forming therebetween water and steam spaces, the inner sheet or head of the section 110 being provided with a depressed combustion-chamber, a series of horizontally-disposed

tubes in the depressed combustion-chamber, having their inner ends in open communication with the inner space of the section and their outer ends closed, the outer ends of the 5 tubes being extended to a point flush with the edges of the section, and water and steam circulating passage-ways connecting the section and the main boiler, substantially as described.

- 10 2. A supplemental section for steam-boilers, consisting in combination, of an outer hull, inner and outer sheets or heads, held spacedly apart by the hull, forming therebetween water and steam spaces, a depressed combustion- 15 chamber on the inner sheet side of the supplemental section, a series of horizontally-disposed tubes in the depressed combustion-

chamber, the tubes being in open communication at one end with the sections water-space, and closed at their outer or free ends, 2 clean-out openings leading through the inner and outer sheets of the section, water and steam circulating passage-ways adapted for connection with suitable similar passage-ways 2 extending from the water and steam spaces of the main boiler, and flanges on the section and main boiler, having suitable perforations adapting them to be secured together by bolts or rivets, substantially as described.

JAMES P. KARR.
